CLAIM

I claim the ornamental design for a tent, as shown and described.

DESCRIPTION

FIG. 1 is a front, left perspective view showing my new design;

FIG. 2 is an alternative front perspective view thereof;

FIG. 3 is a right side perspective view thereof;

FIG. 4 is a rear perspective view thereof;

FIG. 5 is a left side perspective view thereof; and,

FIG. 6 is a top perspective view thereof.
